Primary Examiner—Robert A. Delehanty

(57) **CLAIM**

The ornamental design for a protective glove, as shown and described.

DESCRIPTION

FIG. 1 is a perspective view of the protective glove showing my new design;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a perspective view thereof with the wrist portion of the glove in the open position;

FIG. 8 is a top view thereof with the wrist portion of the glove in the open position;

FIG. 9 is a front view thereof with the wrist portion of the glove in the open position;

FIG. 10 is a perspective view of the protective glove showing a fragmentary broken line to illustrate a human wrist which forms part of the environmental structure of the protective glove; and,

FIG. 11 is a cross sectional view of the protective glove taken along line 11—11 of FIG. 10.
